UNITED STATES PATENT OFFICE.

HOWARD D. COLMAN, OF ROCKFORD, ILLINOIS, ASSIGNOR TO EDGAR S. NETHERCUT, OF EVANSTON, ILLINOIS.

YARN-MASS SUPPORT.

Application filed September 14, 1921, Serial No. 500,512. Renewed December 4, 1925.

This invention relates particularly to yarn carriers and supports for yarn carriers. To illustrate some of the uses to which the invention may be practically applied, attention may be called to Patent No. 1,267,977, granted to me on May 28, 1918, for a machine for rewinding bobbins to form cross-wound yarn masses commonly termed "cheeses", and Patents Nos. 1,274,387 and 1,274,442, both dated August 6, 1918, disclosing a warper creel in which the cheeses may be mounted for rewinding upon a section beam. In the patents referred to, the cross-wound yarn mass is built upon a tubular core. While the yarn mass is being formed, the core is supported upon a hub or roller which is mounted upon ball bearings carried by a pivoted arm of the winder. (For an illustration of such a core-supporting roller, reference may be made to Patent No. 1,329,504 issued February 3, 1920.)

While the cheese is being rewound upon the section beam, it is supported upon a spindle of a so-called trident, the trident consisting of a base having three spindles, each spindle carrying a series of ball-bearing rollers for supporting the cheese cores.

The object of the present invention, generally stated, is to improve upon the constructions shown in the patents alluded to, this object being attained by combining the cheese core with a support adapted to be mounted upon either the winder or the trident.

In the accompanying drawings, Figure 1 is a fragmental view of a trident showing two cheeses mounted thereon, the trident being in the position which it occupies when receiving cheeses at the winder. Fig. 2 is a fragmental view of a trident in the position which it occupies in the warper creel. Fig. 3 is a sectional view showing the cheese core in operative position upon the arm of one of the winding units of the winder. Fig. 4 is an end view of the cheese bearing of the winder. Fig. 5 is an enlarged fragmental sectional view.

In the drawings, A indicates a cheese consisting of yarn spirally wound upon the periphery of a headless cylindrical yarn carrier. The yarn carrier may be said to consist of two sections, namely, a tubular or sleeve-like supporting member B' (Fig. 3) and a roller or cheese core B² mounted upon the member B', ball bearings being inter-

posed between the elements B' and B². In the embodiment which I have selected for illustration herein, the supporting member B' consists of an inner sleeve 1 having a smooth inner surface and adapted to fit upon a spindle *x* on the cheese-supporting arm *x'* of the winder and upon a spindle *y* of the trident *y'*. Surrounding the sleeve 1 are two cones 2 and 3 for the bearings of the roller B, and an intermediate spacer sleeve 4. The parts 2, 3 and 4 are rigidly secured to the sleeve 1 in any suitable manner, as, for example, by expanding one end of the sleeve 1 as at 5, and by turning a nut 6 upon the opposite end of the sleeve 1, said nut having a conical surface to engage the cone 2.

The cheese core B² is formed of two metal sections 7 and 8 rigidly secured together in a suitable manner. In the present embodiment of the invention, one end of the section 7 is reduced in diameter to fit tightly within one end of the section 8. Each of the sections 7 and 8 has an inwardly-extending annular end wall 9 and 10, respectively. The inner portion of each of said walls is formed to provide a ball race 11. Between the cones 2 and 3 and the ball races 11 are interposed bearing balls 12. A tube or sleeve 13 extends between the end walls 9 and 10 adjacent to the ball bearings. In the ends of the tube 13 are small openings 14 for a purpose to appear hereinafter. The ball races are extended to form lips 15 surrounding the sleeve 4.

In order to lubricate the ball bearings, a suitable quantity of oil *o* is placed within the cheese core B². By reason of the well known tendency of oil to creep over a surface, sufficient oil reaches the ball bearings to keep the latter properly lubricated. When rotated the oil is spread over the inner periphery of the cheese core B², and when the cheese is stopped some of the oil creeps over the surfaces and enters the bearings. If an excessive amount of oil were fed to the bearings it would go on out through them and get onto the yarn which is wound upon the cheese core. To prevent this is one of the functions of the sleeve 13, the notches 14 permitting a limited amount of oil to pass. The lip 15 increases the distance the oil must creep and thus assists to reduce to the desired extent the amount of oil that reaches the bearings.

When the supply of oil requires renewal, the nut 6 is unscrewed and the bearings taken apart by disassembling the cones 2 and 3 and the sleeve 4. One end of the cheese core is then closed by inserting a cork into the annular lip 15, after which oil is poured into the space between said lip and the sleeve 13, the oil flowing through the notches 14 into the interior of the cheese core.

The interior of the yarn carrier element 7 constitutes a chamber to contain oil, and the notched sleeves 13 forms means to restrict the passage of oil from said chamber to the ball bearings.

At each end of the combined cheese core and supporting member is means for cushioning the fall of the device when dropped upon a trident spindle. The means herein shown for this purpose comprises a diaphragm or disk 16 formed integral with the outer end of the cone 2 and lying within a depression 9^a in the end wall 9. A generally similar diaphragm 17 is formed upon the outer end of the cone 3 and lies within a depression 10^a in the end wall 10.

The means for releasably locking the supporting member B' upon the cheese arm of the winder may partake of various forms.

In the present instance the cheese arm is provided with a generally cylindrical shell or housing 18 surrounding the base of the spindle x, said housing having an end wall 19. In the peripheral wall of the housing 18 are two diametrically opposite openings. Locking balls 20 project partially through these openings, being held pressed against the walls of the openings by a semicircular leaf spring 21. Rigidly secured to the diaphragm 17 is a ring 22 adapted to encircle the housing 18, said ring having an inturned annular flange 23 fitting slidably upon said housing and adapted to be engaged by the balls 20, as shown in Fig. 3. It will be seen that the combined cheese core and supporting member may be latched in operative position upon the cheese arm by slipping the combined device onto the spindle x and forcing the flange 23 past the balls 20. When the cheese is to be removed from the winder, the operator takes hold of the cheese and pulls it off the cheese arm, the balls 20 yielding to allow the flange 23 to pass.

In order to prevent or lessen the possibility of yarn being accidentally wound around the ring 22 or getting between said ring and the housing 18, there is fixed to the end wall 10 a spool or annular flange 24. The flange 24 surrounds the diaphragm 17 and the ring 22 and is of sufficient width to project into an annular depression 25 in the cheese arm surrounding the housing 18, the flange 24 thus extending across the gap between the cheese core and the cheese arm.

In practice, before placing the combined

cheese core and supporting member upon the cheese arm, the operator strips off any yarn that may be upon the ring 24 or that may by some possibility be on the housing 18 or the spindle x. The combined cheese core and supporting member is placed upon the cheese arm and latched, as hereinbefore described. The latch holds the cheese in definite position by pulling the diaphragm 17 against the end wall 19 of the housing 18. The ring 22 does not rotate, and hence if the yarn being unwound from the bobbin should in some way reach said ring, the latter will not act to unwind yarn from the bobbin.

When the formation of the cheese has been completed, the operator pulls the cheese off the cheese arm, the balls 20 yielding to allow the flange 23 to pass. The operator drops the cheese upon a spindle of a trident supported conveniently at hand. The cheeses are placed upon the trident in invariable position, with the latch side downward. It will be apparent that the fall of the first cheese to be placed upon the trident spindle is cushioned by the diaphragm 17. When the next cheese is placed upon the spindle, the ring 22 of said cheese rests upon the diaphragm 16 of the first cheese, the fall of the second cheese being cushioned by reason of the resiliency of the diaphragm 16 and 17 of the first cheese and the diaphragm 17 of the second cheese. By thus cushioning the fall of the cheeses, any tendency toward sliding of the yarn mass upon the cheese core is counteracted, and the combined cheese core and supporting member is protected from being knocked out of shape, thus incidentally reducing the liability to the production of so-called "cobwebs" in the operation of the winder.

The diaphragms 16 and 17 constitute structures in the nature of circular flanges which are secured to the ends of the tubular support B¹ are of sufficient diameter to overlie and underlie the ends of the yarn-carrier B² and thus keep the latter out of contact with other units above and below it. If the blow of a falling unit were received by the yarn carrier B² of a lower unit, the stresses would be transmitted to the tubular support B¹ of such lower unit through the ball bearings, thus imposing excessive stresses on the bearings. With the construction herein shown, the weight of superincumbent cheeses is borne by the column of tubular supports.

With previous styles of trident rollers, cheeses being unwound in the creel would occasionally run into contact with adjacent cheeses, thus causing one thread to become slack. The slack thread sometimes caused stoppage of the warper and even when it did not stop the warper it was objectionable because of the resulting lack of uniformity in thread tension. An accumulation of lint and

yarn between the trident rollers also caused one cheese to drive another with the above-mentioned results. Moreover, the cheeses would sometimes bound or rotate with a rolling action due to their being out of balance, thus causing more tension on the thread.

It will be seen that through the present invention the cheese arms of the winder and the tridents of the warper creel are greatly simplified and cheapened, ball-bearing rollers on the cheese arms and the tridents being rendered unnecessary. The pivot on the cheese arm becomes merely a stud or spindle, while the trident becomes simply a base with three plain spindles.

There being no shoulders or other projections within the sleeve 1, the cheese core may be easily slipped on the spindle α .

I claim as my invention:

- 20 1. The combination of a sleeve, two cones and an intermediate spacer sleeve surrounding the first sleeve, means on one end of the first sleeve to prevent movement of the adjacent cone in one direction, a nut on the opposite end of the first sleeve to confine said cones and spacer sleeve upon the first sleeve, each of said cones having a diaphragm attached thereto, a yarn carrier having recessed ends, ball races on the yarn carrier, bearing balls between the ball races and said cones, a yarn-receiving flange attached to one end wall of the yarn carrier and surrounding the adjacent diaphragm, and a locking ring connected to the last mentioned diaphragm.
- 25 2. In a winder, the combination of an arm having a spindle fixed thereto, a housing surrounding the base of the spindle, said arm having an annular recess surrounding the housing, a tubular member adapted to fit upon said spindle, a locking member connected to one end of said tubular member, locking means associated with the housing to coact with said locking member, a yarn carrier rotatably mounted upon said tubular member, and a yarn-receiving flange attached to one end of the yarn carrier and encircling the locking means and extending into the annular recess in the arm.
- 30 3. In a winder, the combination of an arm having a spindle fixed thereto, a housing surrounding the base of the spindle, said arm having an annular recess surrounding the housing, a tubular member adapted to fit upon said spindle, a yarn carrier rotatably mounted upon said tubular member, and a yarn-receiving flange attached to one end of the yarn carrier and extending into the annular recess in the arm.
- 35 4. In a winder, the combination of an arm having a spindle fixed thereto and having an annular recess surrounding the base of the spindle, a tubular member adapted to fit upon said spindle, means preventing free rotation of the tubular member on said spindle, a yarn carrier mounted upon said tubu-

lar member for free rotation and so connected to said tubular member that said tubular member and said yarn carrier may be slipped as a unit on and off the spindle, and a yarn-receiving flange attached to one end of the 70 yarn carrier and extending into the annular recess in the arm.

5. The combination of a yarn carrier chambered to contain oil, a supporting member, ball bearings between the yarn carrier and the supporting member, an annular lip extending from the ball bearings toward the center of the yarn carrier, and an axially-located sleeve within the yarn carrier, said ball bearings and lips being surrounded by 80 said sleeve, the latter having an opening in each end for the passage of oil.

6. The combination of a yarn carrier chambered to contain oil, a supporting member, ball bearings between the yarn carrier and the supporting member, and an axially-located sleeve within the yarn carrier, said ball bearings being surrounded by 85 said sleeve, the latter having an opening in each end for the passage of oil.

7. The combination of a sleeve, two cones and an intermediate spacer sleeve surrounding the first sleeve, means on one end of the first sleeve to prevent movement of the adjacent cone in one direction, and a nut on the opposite end of the first sleeve to confine said cones and spacer sleeve upon the first sleeve.

8. In a winder, the combination of an arm having a spindle, a tubular member adapted to fit upon the spindle, means for locking the tubular member upon the spindle, said locking means comprising interengaging parts on the tubular member and the arm, a yarn carrier, and ball bearings by which the yarn carrier is rotatably supported upon 100 the tubular member.

9. The combination of a yarn carrier having an annular recess in one of its ends, a tubular member extending axially of and rotatably supporting the yarn carrier, and a cushioning diaphragm attached to said tubular member and lying within said recess said 110 yarn carrier and tubular member being connected together for handling and transportation as a unit.

10. The combination of a yarn carrier having an annular recess in one end, a support extending axially of and rotatably supporting the yarn carrier, and a cushioning member attached to said support and extending within said recess said yarn carrier and said support being connected together for handling and transportation as a unit.

11. The combination of a cheese core, a support on which the cheese core is mounted, and cushioning devices at the opposite ends of said support.

12. The combination of a cheese core, a support on which the cheese core is rotatably mounted, and a cushioning device on said 130

support said cheese core and said support being connected together for handling and transportation as a unit.

13. The combination of a yarn carrier having an annular recess in one of its ends, a tubular member extending axially of and rotatably supporting the yarn carrier, said yarn carrier and tubular member being connected to form a unit, and a metallic cushioning diaphragm attached by its central portion to said tubular member and lying within said recess.

14. The combination of a cheese core and a cushioning device connected to one end of the cheese core said cushioning device consisting of a metallic diaphragm, the central portion of which is secured to the cheese core, the peripheral portion of the diaphragm being free to yield under pressure.

15. The combination of a yarn carrier, a tubular member upon which the yarn carrier is rotatably mounted, the yarn carrier having an annular recess in one of its ends, a cushioning diaphragm attached to said member and lying within said recess, and a locking ring attached to and extending outwardly from the diaphragm.

16. The combination of a cheese core, a tubular member upon which the cheese core is rotatably mounted, a cushioning device attached to one end of the tubular support, and a locking member attached to the cushioning device.

17. The combination of a cheese core, a tubular member upon which the cheese core is rotatably mounted, a diaphragm attached to one end of the tubular support, and an annular locking member attached to the diaphragm.

18. The combination of a cheese core, a support upon which the cheese core is rotatably mounted, and an annular locking member attached to one end of said support.

19. The combination of a yarn carrier, a support extending axially of and connected to the yarn carrier for rotatably supporting the latter, a metallic cushioning diaphragm attached by its central portion to said support, and a ring attached to the periphery of the diaphragm and projecting beyond the end of the yarn carrier.

20. A cheese core, a tubular support therefor, and ball bearings between the cheese core and said support, said parts being combined into a unitary device.

21. A cheese core, a support therefor, and an anti-friction bearing between the cheese core and the support, said parts being combined into a unitary device.

22. A yarn carrier in the form of a roller, a tubular support for said roller, and ball bearings between the roller and the support, said parts being connected together to constitute a unit.

23. A yarn carrier adapted for use inter-

changeably in a winder and a warper creel, said yarn carrier consisting of a sleeve adapted to fit slidably on the spindle of a winder or the spindle of a warper creel, a cylindrical headless structure on which yarn may be wound, antifriction bearings by which said structure is rotatably mounted on and connected to the sleeve for transportation between the winder and the creel as a unit, a locking element on one end of the sleeve, and an annular yarn-receiving flange secured to and projecting beyond one end of said structure and surrounding said locking element.

24. A yarn carrier adapted for use interchangeably in a winder and a warper creel, said yarn carrier consisting of a sleeve adapted to fit slidably on the spindle of a winder or the spindle of a warper creel, a cylindrical headless structure on which yarn may be wound, said structure being rotatably mounted on the sleeve and united to the sleeve for transportation between the winder and the creel as a unit, an annular locking element on one end of the sleeve, and an annular yarn-receiving flange secured to and projecting beyond one end of said structure and surrounding said annular locking element.

25. A yarn carrier adapted for use interchangeably in a winder and a warper creel, said yarn carrier consisting of a sleeve adapted to fit slidably on the spindle of a winder or the spindle of a warper creel, a cylindrical headless structure on which yarn may be wound, said structure being rotatably mounted on the sleeve and united to the sleeve for transportation between the winder and the creel as a unit, and an annular yarn-receiving flange secured to and projecting beyond one end of said structure.

26. A yarn carrier adapted for use interchangeably in a winder and a warper creel, said yarn carrier consisting of a sleeve adapted to fit slidably on the spindle of a winder or the spindle of a warper creel, a cylindrical headless structure on which yarn may be wound, antifriction bearings by which said structure is rotatably mounted on and connected to the sleeve for transportation between the winder and the creel as a unit, and cushioning means on each end of said sleeve.

27. The combination of a yarn carrier, a tubular member upon which the yarn carrier is rotatably mounted, said yarn carrier and tubular member being connected together for handling and transportation as a unit, a cushioning diaphragm attached to one end of said tubular member, a locking ring attached to and extending outwardly from the diaphragm, and an annular yarn-receiving flange secured to the end of the yarn carrier and surrounding said diaphragm and locking member.

28. The combination of a yarn carrier, a tubular member upon which the yarn carrier is rotatably mounted, said yarn carrier and tubular member being connected together for handling and transportation as a unit, a cushioning diaphragm attached to one end of said tubular member, and an annular yarn-receiving flange secured to the end of the yarn carrier and surrounding said diaphragm.

29. The combination of a yarn carrier, a tubular member extending axially of and rotatably supporting the yarn carrier, said tubular member and yarn carrier being connected together for handling and transportation as a unit, and a cushioning diaphragm attached to one end of said tubular member.

30. A yarn carrier adapted for use interchangeably in a winder and a warper creel, said yarn carrier consisting of a sleeve adapted to fit slidably on the spindle of a winder or the spindle of a warper creel, a cylindrical headless structure on which yarn may be wound, said structure being rotatably mounted on the sleeve and united to the sleeve for transportation between the winder and the creel as a unit, and a locking element on one end of the sleeve.

31. A cheese core having a cylindrical peripheral surface on which a cheese may be built, and an annular yarn-receiving flange rigidly secured to one end of the cheese core and of smaller diameter than said peripheral surface.

32. The combination of a cylindrical carrier on which yarn is intended to be wound, said carrier having a chamber therein to contain oil, a supporting member, an anti-friction bearing between the yarn carrier and the supporting member, and means to restrict the passage of oil from said chamber to said bearing.

33. The combination of a yarn carrier chambered to contain oil, a supporting member, an anti-friction bearing between the yarn carrier and the supporting member, and an axially located sleeve within the yarn carrier, said sleeve surrounding said bearing and having an opening for the passage of oil to the bearing.

34. The combination of a creel spindle, a

plurality of yarn-supporting units removably mounted on said spindle, each of said units consisting of a tubular support 55 adapted to be slipped over the spindle, and a yarn carrier rotatably mounted on said support and held against endwise movement with relation to the support, the supports of said units being adapted to make end 60 contact with each other and thereby keep the yarn carriers out of contact with each other.

35. A yarn-supporting unit consisting, in combination, of a yarn carrier, a support for the yarn carrier, ball bearings between the yarn carrier and its support, said bearings serving to connect the two, and yieldable means projecting from one end of the support beyond the yarn carrier to 70 protect the ball bearings from damage when the unit is dropped with said projecting means directed downwardly.

36. A yarn-supporting unit consisting, in combination, of a yarn carrier, a support 75 for the yarn carrier, ball bearings between the yarn carrier and its support, said bearings serving to connect the two, and means to protect the ball bearings from damage when the unit is dropped endwise. 80

37. A yarn-supporting unit comprising, in combination, a yarn carrier, a tubular support on which the yarn carrier is rotatably mounted, and a structure in the nature of a circular flange secured to each end of 85 the tubular support and of sufficient diameter to overlie and underlie the ends of the yarn carrier to keep the latter out of contact with other units above and below it.

38. A yarn-supporting unit consisting, in 90 combination, of a yarn carrier, a tubular support for the yarn carrier, two ball bearings between the yarn carrier and its support, one near each end of the support, said bearings serving to connect the yarn car- 95 rier and the support, and means to protect the upper ball bearing from damage in the event that another unit be dropped upon the first-mentioned unit while the latter is vertically positioned. 100

In testimony whereof, I have hereunto set my hand.

HOWARD D. COLMAN.
